UNITED STATES PATENT OFFICE

155,661

DESIGN FOR A BOTTLE CARRIER

Ernest T. Wahlbom, Rockford, Ill., assignor to Griggs-Wahlbom, Inc., Rockford, Ill., a corporation of Illinois

Application June 10, 1948, Serial No. 146,876

Term of patent 14 years

(Cl. D58—4)

To all whom it may concern:

Be it known that I, Ernest T. Wahlbom, a citizen of the United States, residing at Rockford, in the county of Winnebago and State of Illinois, have invented a new, original, and ornamental Design for a Bottle Carrier, of which the following is a specification, reference being had to the accompanying drawings forming a part thereof.

In the drawings:

Fig. 2 is a cross section taken along the line 2—2 of Fig. 1.

I claim:

The ornamental design for a bottle carrier, substantially as shown.

ERNEST T. WAHLBOM.
